UNITED STATES PATENT OFFICE.

OTTO C. BOEGE, OF NEW YORK, N. Y.
FILM-WINDING DEVICE.

1,177,985.

Specification of Letters Patent. Patented Apr. 4, 1916.

Application filed April 26, 1915. Serial No. 24,141.

To all whom it may concern:

Be it known that I, OTTO C. BOEGE, a citizen of the United States, and resident of New York, in the county and State of New York, have invented an Improved Film-Winding Device, of which the following is a specification.

One of the defects in film winding devices for motion picture machines consists in the fact that the film, after having been used in the projecting apparatus, is so wound up that its front end is located near the center of the reel.

It thus became necessary that after winding the film onto the take-up reel in the customary manner so that the front end of the same is near the center of the reel, to rewind the same onto another reel, in order to get the front end of the film on the outer side of the reel.

Efforts have been made to eliminate the rewinding and the present invention is intended to provide a simple, inexpensive device wherein this object is accomplished. This is brought about by constructing an organization of stationary parts, including radially or tangentially and resiliently disposed rollers, and an organization of rotatable parts, to which the front end of the film is appropriately secured, coöperating with the stationary parts so that the film, as it leaves the projecting apparatus, may be directly wound so that its front end is on the outer periphery of the reel and ready to be re-used in the projecting apparatus of the motion picture machine, without the necessity of rewinding the same.

The drawing illustrates the invention in Figure 1, in an elevation and, in part, in cross section of the organization of the stationary parts. Fig. 2, is a vertical transversal cross section in the axis of the device, Figs. 3, 4 and 5, are views, in part in cross section, of the rollers, and Fig. 6, is a view of the front end of the film.

A base 1, carries a bracket 2, for supporting a stationary plate 3, having a portion cut away, as at 4. A mandrel 5, is secured to the plate 3, and provided with a key 6, for preventing rotation of a plug or cylinder 7. This cylinder is surrounded by a sleeve 8, also secured to the plate 3, and a second similar, but outer sleeve 9. A number of spring barrels 10, preferably of cylindrical shape, are secured to the inner sleeve 8, as well as to the outer sleeve 9, and

tangentially disposed and spirally distributed along the sleeves, so that they may be of considerable length and firmly held in place.

Each of the barrels contains a helical spring 11, surrounding a rectilinearly reciprocatable rod 12, provided with a collar 13. One end of the spring rests against the bottom of the barrel and the other end against the collar 13. In order to prevent the rods leaving the barrels, the latter are provided with a flange 14. The means for assembling the barrels and the rods is of no importance and does not form part of the present invention. Each rod carries or is extended into a roller shaft 15, in some cases secured to a bracket 16. There are five rollers shown, the number of which may however be increased or decreased, as desired. The rollers 17, are preferably disposed as shown in Fig. 2.

One roller, such as the one shown in Fig. 4, is located on the right side and adjoining the plate 3, another roller, such as shown in Fig. 5, to the left of and adjoining the first roller, a third roller, such as shown in Fig. 3, to the left of and adjoining the second roller, a fourth, similar to the one shown in Fig. 5, but reversed in position, to the left of and adjoining the third roller, and a fifth, similar to the one shown in Fig. 4, but reversed in position, and without the film guide, to the left of and adjoining the fourth roller. The operative position of the roller shown in Fig. 3, is indicated in dotted lines, as a circle within the roller, the position of the roller shown in solid lines, is only intended to more clearly illustrate the relation of the roller to its holding means. The roller on the right hand side of Fig. 2, and on the top of Fig. 1, is provided with a film guide 18, for receiving the film 19, from any suitable outside source, such as a motion picture projecting machine, and for leading the same onto the retaining rollers.

The loose or rotatable members of the device, comprise the plate 20, supported by and rotatable on the mandrel 5, and held thereon by a nut 21, or other suitable means. It may be rotated by any convenient means, such as a crank, gear, etc. This plate carries a cylindrical mantle or detachable flange 22, preferably made of parts hinged together, at two points diametrically opposite, one of the points provided with locking means, which mantle is secured to the plate

20, by convenient fastening means, such as the thumb screws 23. The mantle is provided with flanges 24, surrounding the outer edges of the stationary plate 3, as well as 5 of the movable plate 20, and is movable, of course, with the latter. The mantle is provided on its inner side with a button 25, or other device, for receiving the opening 26, of the front end of the film 19.

10 The operation of the device is, as follows: The film 19, as it comes from the projecting apparatus of a motion picture machine, or from some other source of supply, is carried through the slot of the film guide 15 18, and then secured with its opening 26, to the conveniently positioned button 25, of the mantle 22. In now rotating the loose disk 20, the film is so wound against the inner side of the cylinder, that it forms the outer 25 layer of the reel. Any succeeding layer will be rolled onto the inner side of the preceding outer layer and forced thereon by means of the resiliently supported rollers 17, until the entire film is wound up, and the springs 30 11, compressed to their limit. In re-using the film, or unwinding the same, the mantle 22, is taken off the plate 20, the outer film end removed from its holding button 25, and the film reel placed again onto the take-off reel of a projecting machine.

Claims.

1. The combination with a rotatable member having means thereon for holding the end of a film, of a stationary cylinder arranged coaxially with said member, a series of barrels arranged tangentially on said cylinder, a spring controlled rectilinearly reciprocatable rod in each barrel, and a roller at the free end of each rod adapted

to guide said film during the rotation of 40 said member so that successive windings of said film are located on, and in contact with the inside of the preceding winding.

2. The combination with a rotatable member, of a detachable flange thereon, means 45 on said flange for holding the end of a film, a stationary member arranged coaxially with said rotatable member, a series of barrels tangentially arranged on said stationary member, a spring controlled rectilinearly 50 reciprocatable member in each barrel, and a roller at the free end of each reciprocatable member adapted to guide said film during the rotation of said rotatable member whereby succeeding layers are placed within preceding layers of 55 said film.

3. The combination with a rotatable member, of a detachable flange thereon, means on said flange for holding the end of a film, a stationary member arranged coaxially 60 with said rotatable member, a series of barrels tangentially arranged and spirally distributed on said stationary member, a spring controlled rectilinearly reciprocatable member in each barrel, and means at the free end 65 of each reciprocatable member adapted to guide said film during the rotation of said rotatable member whereby succeeding layers are placed within preceding layers of 70 said film.

Signed at New York, in the county and State of New York, this 10th day of February, 1915.

OTTO C. BOEGE.
